2 Claims

ABSTRACT OF THE DISCLOSURE

This invention consists of a high explosive system comprising a flexible unfoamed polyether urethane binder and RDX (or HMX) alone or with atomized aluminum. The

2

used explosive which melts at 177.62° F. However, RDX which melts and decomposes at 399.2° F. and HMX which melts and decomposes at 536° F. are too shock sensitive for use in the pure state in bombs or other ordnance devices and must be mixed with less shock sensitive or shock insensitive materials. The greater the amount of shock insensitive materials the lower the shock sensitivity of the explosive. Tests have shown that the specimens below when subjected to the shock of a U.S. Army Corps of Engineers special blasting cap J-2 did not detonate in 2 trials. The specimen can be detonated with a 160 gram charge of pentaerythritol tetranitrate more commonly known as PETN.

The polyether prepolymer which is the main binder constituent is mixed with the other ingredients before

TABLE I

Percent of mix		Specimen size and shape	Specimen temp., ° F	Detonator (imbedded in center of cube)	Effect on specimen
RDX	Polyether urethane rubber				
70.....	30	2 in. cube....	60	J-2	Specimen broke apart. Did not detonate.
65.....	25	10 ..do.....	60	J-2	Do.
67.....	28	5 ..do.....	60	J-2	Do.

explosive is cast and cured in an armament case adhering tightly to the case, reinforcing it and forming a tough, water resistant, and heat resistant (350° F.) explosive with low impact sensitivity. It can be cycled from -65° F. to 350° F. without cracking or separating from the armament case.

This application is a continuation in part of my copending application Ser. No. 542,432 filed Apr. 12, 1966, now abandoned.

This invention relates to the manufacture of high explosive compositions. More particularly it relates to a method of binding together explosive particles of RDX (Cyclotrimethylenetrinitramine) or HMX (Cyclotetramethylenetrinitramine) alone or with atomized aluminum powder. The binding material is an unfoamed polyether urethane rubber. The specific gravity of the explosive is approximately 1.6.

It is the primary object of this invention to provide an explosive system which when poured and cured in a mold or military armament case forms a flexible, tough, and moisture resistant high explosive which adheres to the armament case and which can be cycled over a temperature range from -65° F. to 350° F. without cracking, melting, or separating from the case. In the case of HMX filled explosive, the upper limit is approximately 400° F. An additional objective is to provide an explosive mixture which not only can be cast and cured in the armament case but which will adhere tightly to and reinforce the armament case. Examples of this requirement are armaments which are designed to penetrate hard surfaces before exploding.

Tests have shown that the shear strength at the interface between the explosive and case exceeds 900 pounds per square inch or bonded surface. The explosive of this invention when poured and cured to a solid tough composition does not change in properties when immersed in water for periods as great as 180 days at 160° F. The period for which it will withstand this treatment in excess of 180 days was not determined. RDX (or HMX) without additives has 1.5 times the explosive power of 2,4,6-trinitrotoluene, more commonly known as TNT, a commonly

adding a curing agent. Preparation of the prepolymer is as follows:

Mix under a nitrogen atmosphere 46 parts of 2000 molecular weight polypropylene glycol and 31 parts of 3000 molecular weight propylene oxide adduct of 1,2,6-hexanetriol and hold at 150° F. until both components are liquid. Add 18.4 parts of 2,4-toluene diisocyanate; and 4.6 parts of 2,6-toluene diisocyanate by means of a dropping funnel. Continue heating until a reaction temperature of 212° F. is reached. Hold this temperature until a viscosity of 5000 cp. at 77° F. is attained. The quantity of the tolylene diisocyanate isomer mix can be varied to arrive at the optimum NCO content. A 5 percent NCO content has been found satisfactory in the subject application. The 3000 molecular weight propylene oxide adducts of glycerin or trimethylolpropane may be used in place of the propylene oxide adduct of 1,2,6-hexanetriol with some variations in physical properties. Some variations in preparation of the above polyether urethane prepolymer can of course, be tolerated. Therefore, the preparation process is intended to be representative and not limiting.

The following examples are illustrative of my invention and as with the prepolymer they are intended to be representative and not limiting.

EXAMPLE I

Place 23.85 parts of polyether prepolymer in a mixing bowl held at 200° F. Add 75 parts of RDX (or HMX) and mix until homogeneous. Add 1.15 parts of molten trimethylolpropane and mix until the trimethylolpropane is well distributed but not more than approximately five minutes. Mix in a vacuum mixer or evacuate the mix prior to pouring. As the mix has a pourable life of only 30 minutes, pour immediately into the molds coated internally with a release agent such as Teflon or into armament cases not coated with a release agent such as bomb cases. Cure in the mold or armament case at 200° F. for approximately 15 hours. To prevent foaming, all ingredients used in making the explosive must be kept water free.

EXAMPLE II

Place 17.17 parts of the polyether prepolymer in a mixing bowl held at 200° F. Add 23 parts of finely atomized

aluminum powder and 59 parts of RDX (or HMX) and mix until homogeneous. Add .83 part of molten trimethylolpropane and mix until the trimethylolpropane is well distributed but not more than approximately 5 minutes. From this point the procedure is the same as that for Example I.

In both samples the curing agent trimethylolpropane can be replaced by other polyols such as a mixture of trimethylolpropane and 1,4-butanediol, or amines. These may cause variations in the time before the mixture is too thick to pour (pot life). A mixture of .9 part of trimethylolpropane and 3.2 parts of 1,4-butanediol per hundred is approximately equal in effect to 4.7 parts of trimethylolpropane per hundred. Most amines result in too short a pot life to allow casting. Three eighth inch cubes of RDX explosives made by the process of Examples I and II were heated to a temperature of 350° F. for one hour without melting. A 5 inch by 5 inch x 2.8 inch block of RDX explosive made by the process of Example II was cycled from -65° F. to 180° F. over a 24 hour period (16 hours at -65° F. and 8 hours at 180° F.) 30 times without any evidence of cracking or other physical deterioration. Because of the greater flexibility at higher temperatures, it was not considered necessary to cycle higher than

180° F. to show the capability of cycling to 350° F. in view of the results with the $\frac{3}{8}$ inch cubes.

I claim as my invention:

1. A castable explosive system comprising approximately 15 to 50 weight percent of unfoamed polyether urethane rubber and 50 to 85 weight percent of cyclotrimethylenetrinitramine or cyclotetramethylenetrinitramine.

2. A castable explosive system of claim 1 in which atomized aluminum particles in the amount of 5 to 35 percent are substituted for equal weight percents of RDX or HMX.
